UNITED STATES PATENT OFFICE.

DENNIS G. LITTLEFIELD, OF ALBANY, NEW YORK.

IMPROVEMENT IN AUTOMATIC OVEN-SHELVES.

Specification forming part of Letters Patent No. 222,357, dated December 9, 1879; application filed June 25, 1879.

To all whom it may concern:

Be it known that I, DENNIS G. LITTLEFIELD, of the city and county of Albany, and State of New York, have invented certain new and useful Improvements in Automatic Oven-Shelves, of which the following is a full and exact description.

My invention consists in certain modifications of well-known devices for automatically raising stove-oven shelves, hereinafter described, and specifically pointed out in the claim.

In the drawings, Figure 1 is a horizontal section of a portion of the oven-door, showing it open and the shelf extended; Fig. 2, a vertical section of the same on the line X X; Fig. 3, a section showing the door closed and the shelf raised to an upright position; and Fig. 4 is a bottom view of the shelf, having its outer corner, next to the oven-door, cut away or rounded off.

As shown in the drawings, A is the bottom oven-plate; B, the front oven-plate; C, the back oven-plate; D, the side plate of the stove; E, the oven-door, hinged in the usual manner to the side plate, D. F is the shelf, which is provided with pintles f and f', upon which it turns, and which permit it, when in a horizontal position, to extend beyond the side plate, D, and on a level with the bottom oven-plate, A. The pintle f enters an aperture formed for it in the back oven-plate, C, and the pintle f' lies between a stop upon the bottom oven-plate, A, and the side plate, D. A point or projection, f'', on the pintle f' occupies the space left for the purpose between the stop a and front oven-plate, B, which holds the shelf from being pushed endwise.

By this arrangement of the pintles and their bearings the shelf is rendered portable, and can be taken out and replaced for repairs, or for other purposes, without difficulty; or if by accident the shelf is destroyed, there is left no deformity of the oven plates or door, as is the case where the shelf is raised by a door made specially for that purpose, or where complex machinery is made use of for that purpose; besides, with this arrangement the shelf on being worn out can be replaced by one from the factory.

f³ is a projection pendent from the bottom of the shelf at its end nearest the hinge of the door. Said projection is adapted to engage with the lower angle, e, of the panel of the door, which, in closing, bears against said projection and raises the shelf into the position shown in Fig. 3, the end of the shelf being cut away or rounded, so that the door will not strike it to interfere with the action of the angle e of the door-panel and the projection f³ upon the shelf.

When the shelf is in an upright position, as shown in Fig. 3, it rests in the sunken panel of the door with its center of gravity falling outside of its pivoted bearings, so that when the door is opened the shelf will follow it until it finds a horizontal position, as shown in Fig. 1.

Oven-shelves to be automatically raised to a perpendicular position by closing the oven-door have heretofore been made in various ways. Some have used complicated machinery; others a cam or projection upon the door, which projected into the oven when the door was closed.

The first-mentioned method is objectionable by reason of its cost and the liability of the parts to soon wear out and become useless, while the last-mentioned method is objectionable for that such cam or projection, extending into the oven when the door is closed, occupies a portion of the oven-space. It is also a deformity to the door when open, and is in the way when the door is to be lined with tin-plate or sheet iron. It is also in the way when polishing the edge of the door, all of which objections are obviated by my invention.

What I claim as my invention is—

The combination, in an oven-door having a sunken panel, of a bearing or angle, e, lying within the plane of contact between said door when closed and the side plate of the stove, and a shelf having its corner cut away or rounded, and provided with a projection, f³, substantially as and for the purposes above set forth.

DENNIS G. LITTLEFIELD.
